REFRIGERATOR HAVING AN AUTOMATICALLY CONTROLLED SECONDARY REFRIGERANT SYSTEM

Raymond E. Tobey, Springfield, Mass., assignor to Westinghouse Electric Corporation, East Pittsburgh, Pa., a corporation of Pennsylvania

Application May 13, 1947, Serial No. 747,809

18 Claims. (CL 62—125)

1

This invention relates to refrigeration apparatus and more especially to apparatus employing a secondary refrigerant system for cooling a compartment. It is a continuation-in-part of my application, Serial No. 720,888, filed January 8, 1947, now abandoned.

It is an object of this invention to provide a novel means for controlling the refrigerant flow in a secondary refrigerant system.

It is another object of the invention to provide a valve for controlling the flow of a refrigerant in a secondary circuit, which valve is controlled by the temperature of the compartment cooled by said refrigerant.

It is a further object of the invention to accelerate the response of the secondary circuit when refrigeration is required.

These and other objects are effected by my invention as will be apparent from the following description and claims taken in connection with the accompanying drawings, forming a part of this application, in which:

Fig. 1 is a side elevation of a refrigerator cabinet embodying the invention;

Fig. 2 is an enlarged section on the line II—II of Fig. 1, showing the refrigerant passages in a somewhat diagrammatic form;

Fig. 3 is an enlarged sectional view of the flow-controlling device of this invention;

Fig. 4 is a view similar to Fig. 2 but showing a modification of the invention;

Fig. 5 is a sectional view on the line V—V of Fig. 4;

Fig. 6 is an enlarged sectional view of the flow-controlling device of the modification of the invention shown in Fig. 4;

Fig. 7 is a sectional view on the line VII—VII of Fig. 6; and

Fig. 8 is a sectional view on the line VIII—VIII of Fig. 6.

Referring to the drawing for a detailed description of the invention, the reference numeral 10 designates a refrigerator cabinet having an insulated food storage chamber 12 in the upper portion of the cabinet and a machine chamber 14 in the lower portion thereof. The food chamber 12 is divided by an insulated horizontal partition 16 into an upper compartment 18 for the freezing of foods and a lower compartment 20 for general refrigerated storage.

The upper compartment 18 is cooled by a mechanical refrigeration apparatus which includes a primary evaporator coil 22 supplied with a volatile refrigerant by the primary condenser 24 through a capillary tube 26. The primary

2

condenser 24 receives compressed refrigerant vapor through a tube 28 from a refrigerant compressor (not shown) located in a sealed casing 30. The refrigerant compressor withdraws refrigerant vapor from the evaporator coil 22 through a tube 31, a portion of which is in thermal heat-absorbing relationship with a portion 33 of the capillary tube 26. The refrigerant compressor is driven by an electric motor (not shown) also located in the casing 30 and energized through the electrical conductors 32. A thermostatically-controlled switch 34 is located in one of the conductors 32 to regulate the compressor motor. The thermostatic switch 34 is controlled by a metal bellows 36 which is subjected to a pressure of a volatile fluid located in a bulb 38, which bulb is subjected to the temperature of the upper compartment 18. It will be apparent from this that the thermostatic switch 34 controls the motor in response to the temperature of the upper compartment 18 and holds the temperature of this compartment substantially constant.

The lower compartment 20 is cooled by a secondary volatile refrigerant circuit comprising a tube 46 having a condensive portion 48 located in the upper compartment 18 and in heat transfer relationship with the primary evaporator coil 22. The tube 46 also includes an evaporative portion 50 located in the lower compartment 20 to cool the same.

The apparatus for controlling the temperature of the lower compartment 20 comprises a vessel 52 adapted to receive the refrigerant condensed by the condensive portion 48 through a tube portion 54. A conduit portion 56 is located directly below the tube portion 54 to receive the liquid refrigerant issuing therefrom. The conduit portion 56 connects with the lower end of the evaporative portion 50 of the tube 46. The vessel 52 is surrounded by thermal insulating material and is located in a portion of the cabinet 10 which is warmer than the condensive portion 48, so that a slow vaporization of the liquid refrigerant, which may be in the vessel 52, takes place. The vaporization of the refrigerant liquid in the vessel 52 may be increased by placing a portion 55 of the capillary tube 26 in heat transfer relationship with the vessel 52. The portion 55 of the capillary tube 26 is preferably a portion located between the portion 33 in heat-absorbing relationship with the suction tube 31 and the primary evaporator coil 22.

A baffle 58 is interposed between the tube portion 54 and the conduit portion 56 to at times

deflect the liquid refrigerant issuing from the tube portion 54 into the vessel 52. The baffle 58 is pivoted in a support 60 secured to one side of the vessel 52 in such a manner that the baffle 58 may be rotated in clockwise direction from the interposing position just described and shown in full lines in Fig. 3, to a second position shown in dotted lines in Fig. 3. In the second position, the baffle 58 rests against a stop 69 and does not interfere with the gravitational flow of refrigerant liquid from the tube portion 54 to the conduit portion 56. The conduit portion 56 need not be located directly below the tube portion 54 provided the vane 58 is formed to deflect the refrigerant liquid into the tube portion 54 when in the second position.

A horizontal extension 62 is provided at the lower end of the baffle 58 and is engaged by means of springs 61 and 63 between an upper metal bellows 64 and a lower metal bellows 65 which two bellows provide the moving force for the baffle 58. The interior of the upper metal bellows 64 communicates through a tube 66 with a bulb 68. The bellows 64, the tube 66, and a substantial portion of the bulb 68 is filled with a volatile liquid 69, and the bulb 68 is subjected to the temperature of the lower compartment 20 so that the pressure of the volatile fluid 69 expands the bellows 64 and biases the baffle 58 toward the dotted position in Fig. 3 when the temperature of the lower compartment 20 rises.

The movement of the baffle 58 to the dotted position is opposed by the spring 63 and the lower bellows 65. This bellows 65 communicates with a chamber 70, and both the bellows and the chamber 70 are located in the vessel 52 in thermal contact with the contents thereof. The bellows 65 and chamber 70 are charged with a noncondensable gas such as air. The function of the bellows 65 is to compensate for the effects of changes in the pressure of the secondary refrigerant circuit. These changes tend to cause movement of the bellows 64 by acting on the exterior thereof. The changes in pressure of the secondary refrigerant circuit are caused by changes in the temperature of the volatile refrigerant liquid therein, and these changes in temperature, in turn, are caused by the changes in location of this liquid. When the liquid is chiefly in the vessel 52, it is quite cold, and when it is located mainly in the evaporative portion 50 of the tube 46, it is at a higher temperature. The bellows 65 also compensate for changes in the temperature of the primary evaporator coil 22. The purpose of the springs 61 and 63 is to maintain contact with the extension 62 when both bellows 64 and 65 contract.

The volume of the chamber 70 is so chosen that when the temperature of the volatile liquid in the secondary refrigerant circuit decreases (thereby causing a decrease in the pressure in the vessel 52), the resulting tendency of the upper bellows 64 to expand is approximately offset by the tendency of the lower bellows 65 to expand due to the combined effect of the decrease in the pressure in the vessel 52 and the decrease in the temperature of the gas in the bellows 65 and chamber 70. An increase in the temperature of the volatile liquid in the secondary circuit will have the reverse action described above.

The forces of the two opposing bellows 64 and 65 will not neutralize each other completely for all changes in pressures within the vessel 52, but will substantially do so during the normal working range of the secondary circuit. If the

bellows 64 and 65 are of the same size, if the refrigerant in the secondary circuit is dichlorodifluoromethane (F-12), if the fluid in the bellows 64 and bulb 68 is methyl chloride, and if the temperature to be maintained in the lower compartment 20 is about 40° F., then the volume of chamber 70 should be from three to four times the volume of the bellows 65, and the pressure of the gas in the bellows 65 and chamber 70 should be such that it will effect operation of the baffle 58 at the temperature desired in the lower compartment 20.

It will be apparent from the above that whenever the temperature of the lower compartment 20 is considerably above the desired temperature, the liquid refrigerant from the condensive portion 48 of the secondary refrigerant circuit flows downwardly into the evaporative portion 50 thereof and cools the lower compartment 20. On the other hand, when the temperature of the lower compartment 20 is considerably below the desired temperature, the baffle 58 will deflect all of the refrigerant flowing from the condensive portion 48 into the vessel 52 and thereby starve the evaporative portion 50 of the circuit of liquid refrigerant. At the desired temperature, the baffle 58 will assume an intermediate position so that the refrigerant liquid supplied to the evaporative portion 50 will absorb the heat leakage into the lower compartment 20. The volume of the vessel 52 below the entrance to the conduit portion 56 is large enough to contain all of the refrigerant liquid condensable from the refrigerant in the secondary volatile refrigerant circuit by the condensive portion 48 thereof.

Since the vessel 52 is warmer than the condensing portion 48, a portion of the refrigerant liquid in the vessel 52 will continually vaporize and this vapor will be condensed in the condensive portion 48 and be returned to the vessel 52 by the baffle 58. This slight circulation of refrigerant is necessary so that refrigerant liquid is available to flow down the conduit portion 56 when the baffle 58 is moved clockwise. Continued vaporization of the refrigerant liquid in the vessel 52 will supply additional refrigerant vapor to the condensive portion 48, which thereupon is transferred to the conduit portion 56 as refrigerant liquid.

The evaporative portion 50 of the tube 46 is shown as located in the lower compartment 20 for the sake of clearness. In the preferred construction, however, it is located in the heat insulation 51 of the lower compartment 20 and in heat transfer relationship with the inner metal liner 53 thereof.

A modification of the invention is shown in Figs. 4, 5 and 6. In this modification, parts identical with those of the first-described modification are provided with the same reference numerals. The primary evaporator coil 126 and the tube 128 of the secondary volatile refrigerant circuit are shown as located against the side wall of the inner liner 53. The vessel 130 which encloses the actuating mechanism of the secondary circuit is located in the heat insulation 51 of the refrigerator cabinet 131. The bulbs 98 and 132 have similar functions as the bulbs 68 and 38, respectively, of Fig. 2. The housing 134 encloses a thermostatic switch similar to that shown by the elements 34 and 36 of Fig. 2.

A baffle 72 is pivoted on a vertical pin 74 which is affixed to and projects at both ends through a sealed casing 76 of nonmagnetic metal such as

brass. The baffle 72 is in the form of an inclined trough and is carried by a strip of metal 78. Two ears 80 integral with the strip 78 are bent at right angles to the strip 78 and each ear 80 is perforated to provide a bearing which engages the vertical pin 74. The lower ear 80 rests on a spacer 82 encircling the pin 74. A rearward extension 84 of the strip 78 carries a magnetic armature 86 having pole pieces adjacent the walls of the casing 76.

A permanent magnet 88 is supported by arms 90 pivoted on the protruding ends of the pins 74. The pole pieces 92 of the magnet 88 are adapted to swing through the same arc as the poles of the armature 86 and draw the armature 86 with them. The end wall 94 of the casing 76 is rounded to avoid interference with the movement of the magnet 88.

The magnet 88 is moved by a bellows 96 similar in function to the bellows 64 of the modification shown in Figure 3. A spring 100 opposes the pressure of the bellows 96 and the pressure of this spring 100 on the magnet 88 may be varied by adjusting a screw 102. Changing the pressure of the spring 100 changes the temperature at which the lower compartment is maintained. The placing of the bellows 96 outside of the refrigerant passages of the secondary system simplifies the apparatus by eliminating the compensating bellows 65 of Figure 3. The bellows 96 and the magnet 88 are enclosed by walls 103, one of which carries the adjusting screw 102, and another of which carries the bellows 96.

The refrigerant liquid from the condensate portion 48 enters the casing 76 through the tube portion 54 and flows downward through the casing 76 and through a tube 104 into a chamber 106 if the baffle 72 is in the non-interposing position indicated by the dotted lines 108 in Figure 7. On the other hand, if the baffle 72 is in the interposing position shown by the full lines of that figure, the refrigerant liquid from the tube portion 54 will run down the inclined trough 72 of the baffle through a tube 110 into a chamber 112. The chamber 112 is of smaller volume than the chamber 106 and is so arranged with respect to the latter that when the chamber 112 is filled with refrigerant liquid, additional liquid directed to it by the baffle 72 will overflow the chamber 112 and flow along the bottom of the casing 76, through the tube 104, and into the chamber 106. The chamber 112 is located near the outer wall surface of the cabinet 131 to accelerate the evaporation of the liquid from chamber 112.

The volume of the chambers 106 and 112, the quantity of refrigerant liquid in the secondary system, and the height of the elevated portions 116 of the siphon tube 114 are so interrelated that when the chamber 112 and the tube 110 are filled with refrigerant liquid, the remaining refrigerant liquid, if contained in the chamber 106, will be of insufficient height therein to start the flow of the liquid through the elevated portion 116 of the siphon tube 114. This condition is shown by the solid liquid lines in Figure 6. On the other hand, when the chamber 112 is empty and substantially all of the refrigerant liquid is in the chamber 106, the height of the liquid therein will be as shown by the dotted line 118 and the liquid will initiate the siphon action of the tube 114. The liquid in the chamber 106 will thereupon run down the siphon tube 114 to the evaporative portion 136 of the tube 128 until the chamber 106 is substantially empty. This will supply a large quantity of refrigerant liquid to the evaporative

portion 136 in a short period of time so that the system can function with full effectiveness.

The refrigerant liquid will vaporize in the evaporative portion 136, condense in the condensate portion 48, and flow into the casing 76 through the tube portion 54. If the lower compartment 20 is not cooled to the temperature at which the bellows 96 returns the baffle 72 to the full line position shown in Figure 5, the chamber 106 will be filled a second time to the height of the dotted line 118 and a second emptying of the liquid refrigerant content of the chamber 106 into the evaporative portion 136 will take place. This will be repeated a sufficient number of times until the temperature of the lower compartment 20 has been reduced to the desired temperature. At this point, contraction of the bellows 96 allows the baffle 72 to return to the position shown by the full lines in Figure 4.

It will thus be seen that in this modification of the invention only the refrigerant liquid in the chamber 112 is vaporized so that the refrigerant cycle can operate at full effectiveness in a short period of time.

It will be apparent from the above that this invention provides a means for regulating the temperature of a compartment cooled by a secondary volatile refrigerant circuit.

While I have shown my invention in several forms, it will be obvious to those skilled in the art that it is not so limited, but is susceptible of various other changes and modifications without departing from the spirit thereof.

What I claim is:

1. A secondary volatile refrigerating system of the type having substantially the same pressure throughout, said system comprising, in combination, an evaporator adapted to cool a chamber, a vessel adapted to vaporize refrigerant liquid therein at a slower rate than said evaporator, a condenser adapted to condense the refrigerant vapor generated by said evaporator and said vessel, means for conducting the refrigerant liquid formed by said condenser selectively to either said evaporator or said vessel, said means including a bellows subjected on one side to the pressure of a volatile fluid responsive to the temperature of said chamber and on the other side to the pressure of the volatile refrigerant in said system, and means for compensating for the effect of changes in pressure of said volatile refrigerant on said bellows.

2. In a refrigerator comprising an insulated cabinet, a partition therein dividing said cabinet into an upper and a lower food storage chamber, a primary cooling unit for cooling the upper chamber, a volatile refrigerant circuit having a condenser in heat transfer relationship with said cooling unit and an evaporator in heat transfer relationship with said lower chamber, said circuit including a vessel, said condenser being arranged to discharge the condensed refrigerant through a tube into said vessel, a conduit having an entrance opening in said vessel below the exit opening of said tube and above the bottom wall of said vessel, said conduit directing liquid into said evaporator, said vessel being of sufficient capacity below said entrance opening to contain all of the liquid refrigerant condensable by said condenser from the charge of refrigerant in said circuit, the combination with said circuit of a baffle movable from a position whereby the liquid discharged by said tube flows mainly into said conduit to a position whereby said liquid flows mainly into said vessel, and means responsive to

temperature for moving said baffle to either of said positions.

3. The refrigerator defined in claim 2 wherein said temperature is the temperature of said lower chamber.

4. The refrigerator defined in claim 2 wherein said means includes a bellows positioned in said vessel and actuated by the pressure of a volatile fluid subjected to the temperature of said lower chamber.

5. In a refrigerator comprising an insulated cabinet, a partition therein dividing said cabinet into an upper and a lower food storage chamber, a primary cooling unit for cooling the upper chamber, a volatile refrigerant circuit having a condenser in heat transfer relationship with said cooling unit and an evaporator in heat transfer relationship with said lower chamber, said circuit including a vessel, said condenser being arranged to discharge the condensed refrigerant through a tube into said vessel, a conduit having an entrance opening in said vessel below the exit opening of said tube and above the bottom wall of said vessel, said conduit directing liquid into said evaporator, said vessel being of sufficient capacity below said entrance opening to contain all of the liquid refrigerant condensable by said condenser from the charge of refrigerant in said circuit, the combination with said circuit of a baffle movable from a position whereby the liquid discharged by said tube flows mainly into said conduit to a position whereby said liquid flows mainly into said vessel and to positions intermediate said two positions whereby said liquid flows in different proportions into said conduit and into said vessel, and means responsive to the temperature of said lower chamber for moving said baffle to any of said positions.

6. A secondary volatile refrigerating system of the type having substantially the same pressure throughout, said system comprising, in combination, an evaporator adapted to vaporize refrigerant liquid by the absorption of heat, a first chamber and a second chamber, said first chamber being adapted to vaporize refrigerant liquid but at a slower rate than said evaporator, a condenser adapted to receive and condense refrigerant vapor generated by said evaporator and by said first chamber, a siphon tube communicating with a lower portion of said second chamber to conduct a quantity of refrigerant liquid from said second chamber to said evaporator by siphon action when the refrigerant liquid in said second chamber exceeds a predetermined height, said first chamber being so disposed with respect to said second chamber that when said first chamber is filled with refrigerant liquid, further refrigerant liquid supplied to it overflows to said second chamber, and means for conducting refrigerant liquid condensed by said condenser selectively to either said first or said second chamber, the volume of said first and second chambers being such that when a specific quantity of volatile refrigerant liquid is disposed in said system and the system is in normal operation the refrigerant liquid in said second chamber cannot exceed said predetermined height when said first chamber is full and does exceed said predetermined height when said first chamber is empty.

7. The refrigerating apparatus defined in claim 6 wherein said means consists of a movable baffle.

8. The refrigerant system defined in claim 6 including a space cooled by said evaporator and a thermostatic element responsive to the temperature of said space and associated with said

selective conducting means to cause said means to conduct the refrigerant liquid to said first chamber when the temperature of said space is above a predetermined temperature and to conduct the refrigerant liquid to said second chamber when said space is below a predetermined temperature.

9. The refrigerating apparatus defined in claim 8 wherein said means consists of a movable baffle.

10. A secondary volatile refrigerating system of the type having substantially the same pressure throughout, said system comprising, in combination, a quantity of volatile refrigerant liquid, an evaporator adapted to vaporize said refrigerant liquid by the absorption of heat, a first chamber and a second chamber, said first chamber being adapted to vaporize refrigerant liquid but at a slower rate than said evaporator, a condenser adapted to receive and condense refrigerant vapor generated by said evaporator and by said first chamber, a siphon tube communicating with a lower portion of said second chamber to conduct a quantity of refrigerant liquid from said second chamber to said evaporator by siphon action when the refrigerant liquid in said second chamber exceeds a predetermined height, said first chamber being so disposed with respect to said second chamber that when said first chamber is filled with refrigerant liquid, further liquid supplied to it overflows into said second chamber, and means for conducting the refrigerant liquid condensed by said condenser selectively to either said first or said second chamber, the quantity of liquid refrigerant in said system when in normal operation and the volume of said first chamber being so proportioned, that when said first chamber is full, the refrigerant liquid in said second chamber cannot exceed said predetermined height, and when said first chamber is empty, the refrigerant liquid in said second chamber will exceed said predetermined height.

11. The refrigerating apparatus defined in claim 10 wherein said means consists of a movable baffle.

12. The refrigerant system defined in claim 10 including a space cooled by said evaporator and a thermostatic element responsive to the temperature of said space and associated with said selective conducting means to cause said means to conduct the refrigerant liquid to said first chamber when the temperature of said space is above a predetermined temperature and to conduct the refrigerant liquid to said second chamber when said space is below a predetermined temperature.

13. The refrigerating apparatus defined in claim 12 wherein said means consists of a movable baffle.

14. A secondary volatile refrigerating system of the type having substantially the same pressure throughout, said system comprising, in combination, an evaporator adapted to vaporize refrigerant liquid by the absorption of heat, a vessel adapted to vaporize refrigerant liquid at a slower rate than said evaporator, a condenser adapted to condense the refrigerant vapor generated by said evaporator and said vessel, conduit means for conducting the refrigerant liquid condensed by said condenser to said evaporator, said conduit means including a vertical portion having a gap therein through which said liquid drops, and a baffle adapted for movement into and out of said gap, said baffle being formed to deflect the refrigerant liquid flowing from said condenser

into said gap to said vessel when said baffle is moved into said gap.

15. The refrigerating system defined in claim 14 including a quantity of volatile liquid refrigerant in said system not in excess of the capacity of said vessel.

16. The refrigerating system defined in claim 14 including actuating means responsive to heat for effecting the movements of said baffle.

17. The refrigerating system defined in claim 14 wherein said system includes a chamber enclosing said baffle, magnetic material associated with said baffle to move the same, said magnetic material being located within said chamber, magnetic material located outside of said chamber and adapted to move the magnetic material located within said chamber, and means responsive to heat for moving the magnetic material located outside said chamber.

18. Refrigerating apparatus comprising, in combination, a primary refrigerating system of the compressor-condenser-evaporator type, said primary system having a tube for conducting

liquid refrigerant from the condenser to the evaporator, and a secondary volatile refrigerating system having substantially the same pressure throughout, said secondary system comprising a secondary evaporator adapted to vaporize refrigerant liquid by the absorption of heat, a secondary condenser in heat-transfer relation with the evaporator of said primary system, a vessel adapted to trap refrigerant liquid, said vessel being in heat-transfer relation with said tube, and a movable baffle for conducting liquid refrigerant from said condenser selectively to either said secondary evaporator or said vessel.
